UNITED STATES PATENT OFFICE.

EDWARD L. WOOD, OF DETROIT, MICHIGAN.

TOY.

Application filed June 25, 1925. Serial No. 39,469.

The present invention relates to toys of various types such as trucks, excavators and extension ladders wherein two parts are arranged to have relative movement more or less in imitation of mechanical devices in common use, its object being to provide in such devices apparatus which may quickly and at a single operation be set in initial position by the relative movement of said parts in one direction, and thereafter so operate, when released, as to cause the toy to perform its other or reverse phase of movement in "slow-motion" fashion. More especially it is a purpose of the invention to provide actuating mechanism of the class stated above which shall be inexpensive and not liable to get out of order, and which in its operation shall appeal to the natural curiosity of the child.

In the drawings, which show the invention applied to a toy truck,—

Fig. 1 is a side view, parts being broken away, showing the parts in normal or loaded position;

Fig. 2 is a side view, the body being elevated;

Fig. 3 is a plan view, parts being broken away;

Fig. 4 is a longitudinal vertical section through the actuating or body-dumping motor;

Fig. 5 is a front elevation of the follower for the sealing means of the piston;

Fig. 6 is a part section corresponding to Fig. 4 but showing a modification.

In the particular embodiment of the invention shown, one of the relatively movable parts is the truck chassis which may be of conventional construction such as is ordinarily found in toys, including the side bars 1, rear cross-bar 2, intermediate cross-bar 3, wheels 4 and 5, and cab 6.

At their rear ends the side bars carry depending brackets 7 on which the body,—the other relatively movable member,—is mounted to tilt by means of the deep brackets 8, which extend downwardly from the body structure, and pivots 9. The front end of the body, when in lowered position, rests on a chair or chairs which may be formed from a sheet metal Z-bar arranged to rest on and extend across from side bar to side bar to thus brace the chassis. When the body is in lowered position it is retained and held from tilting by

a latch 10 which is mounted on a pin 11 the axis of which extends longitudinally of the vehicle, said latch being preferably of spring metal and having its upper end bent forwardly and upwardly to form a striker 12. The striker 12 is preferably so arranged as to normally take up a position in the path of the front edge of the body as the latter is being lowered, thus causing the latch to be bent forwardly until the upper edge of the body passes beneath the holding part of the latch which then snaps thereto and effectively retains the body in lowered position.

Forward of the rear wheels the side bars are provided with brackets 19 depending considerably therefrom and which may be bent from a strip of metal as shown soldered or otherwise secured in position. These brackets receive and form bearings for the corresponding ends of a cross-bar 20 upon which is mounted, midway of the side bars, motor mechanism comprising a cylinder and piston, the latter being pivotally connected at 21 to a bracket 22 fixed to the lower side of the body. It will be apparent that the parts might be reversed so that the cylinder would be connected to the bracket 22 and the piston to the cross-bar 20, but the arrangement shown is preferable.

The barrel of the cylinder is preferably from a piece of tubing 23 having its lower end closed by a head 24 soldered or otherwise secured thereto and apertured to receive the cross-bar 20, although other constructions such as the sheet metal head 24' and clip 24'' (Fig. 6) may be used. The upper end of the barrel is provided with the head 26 preferably soldered thereto and perforated for the passage of the piston rod 27 to the inner end of which is attached by means of the screw 28 a piston consisting of the metal plates 29 and 30 between which are arranged a cup-shaped leather or other sealing element 31 and a metal pressure plate 32 whose outer edge is notched as indicated at 33 to form a resilient follower for the flange portion of the leather whereby the latter is held closely to the cylinder wall in the outward movement, and permitted to collapse inwardly during the reverse stroke. The piston is provided with a small perforation or passage 34, and between the plate 29 and the head 24 is inserted a helical spring 35 of considerable

tension and of such length as to tend to push the piston to the limit of its outward stroke. Preferably both the head 24 and the plate 29 are flanged to receive the ends of the 5 spring to prevent the latter from contacting directly with the cylinder wall. The head 26 has an inward extension 36 the length of which is greater than the depth of the piston cup so that the leather is precluded from coming in contact with the head when the piston reaches its outermost position. The space between the head 24 and the piston, when in the position shown, is 10 filled with oil or glycerine or other suitable 15 liquid, and as this liquid necessarily comes in contact with the piston rod I have provided a wiper in the form of a fiber or leather washer 40 which is inserted between an outwardly flaring seat 41 in the head 26 and a 20 cap 42 which is screw threaded thereon. Preferably the washer is formed initially with a cross section of the same shape as the space between the cap and the seat so that there is substantially no distortion of the 25 washer as the cap is adjusted thereagainst, which allows an effective wiper action without causing friction sufficient to interfere materially with the movement of the piston. For filling purposes either the head 24 or 30 the head 26 or both is perforated and provided with a threaded removable plug 43-44.

In the development of the device as thus far described I found that there was a tendency, when the truck body was in its 35 lowered position and left idle for a considerable time, for oil to escape through the piston rod gland, this being caused apparently by compression of air in the upper part of 40 the cylinder when the piston rod was fully received therein. This difficulty I have overcome preferably by making the piston rod hollow and by perforating it at the point 45 (Fig. 4), which is so positioned as 45 to be just at the left or inside of the extension 36 and at the upper side of the piston rod when the latter is at the innermost limit of its movement. Pressure within the cylinder is thus freely relieved without causing 50 loss of liquid inasmuch as the inclined cylinder is preferably filled so that the level of the liquid is then below the point 45, and communication with the outside air is immediately cut off when the piston begins its 55 outward movement.

In operation, the parts being in the position shown in Fig. 2, the child presses on the body, swinging it downwardly on its pivots until the latch comes into play as 60 shown in Fig. 1. As the resilient follower allows the flange of the leather cup to swing inwardly this motion may be rapid, whereas when the latch is released the spring returns the piston rod at a very much slower rate 65 determined by the size of the orifice, the

follower then holding the leather closely against the cylinder.

It is desirable, as heretofore pointed out, that the axis about which the cylinder swings, as well as that about which the body 70 tilts, be arranged appreciably below the side bars in that there is thus permitted the use of a cylinder of length sufficient to insure a long stroke together with an effective leverage of the power arm or motor about the 75 pivots 9. The connections may be arranged otherwise.

I claim:

1. A toy comprising a first main member, a second main member arranged to swing 80 in respect to said first member, a spring motor operatively connected to said main members to be tensioned by relative movement of said members in one direction and tending to cause relative movement of said members 85 in the opposite direction, said motor comprising a fluid check for limiting the speed of said relative movement in said opposite direction.

2. A toy comprising a frame, a material 90 holding receptacle carried by said frame and swingable in respect thereto, a spring motor constructed and connected to said frame and said receptacle to be tensioned by moving said receptacle relatively to said frame and 95 adapted thereafter to swing said receptacle in the opposite direction, said motor including means whereby the movement of the receptacle in said opposite direction is restricted to the "slow-motion" type. 100

3. A toy truck comprising a chassis, a body pivoted thereon to tilt, a body-tilting motor interposed between the chassis and body, said motor including a cylinder, a piston, a spring in said cylinder between one 105 end thereof and said piston and arranged to force the piston in a direction to tilt said body, said piston being so constructed as to be moved in the opposite direction by force applied manually to the body to swing it in 110 respect to the chassis, said cylinder having therein liquid and the parts being arranged to permit rapid movement of the piston in a direction such as to tension said spring but constraining the piston to a much slower 115 movement in the direction such as to tilt said body.

4. A toy including a first main member, a second main member shiftable in respect thereto, a spring connected to said members in such manner as to be tensioned by relative movement of said members in one direction and thereafter tending to return said members to their initial relative position, and a hydraulic check through which said 125 spring acts in the return movement to restrict relative movement of said members toward initial position to the "slow-motion" type.

5. Toys comprising two relatively movable parts and a spring motor connected 130

- thereto to cause separation thereof, said motor including a cylinder adapted to contain liquid, a piston housed therein and having a piston rod projecting outwardly through one end thereof, and a spring housed between said piston and the opposite end of said cylinder, said piston being so constructed as to be readily movable toward said last named end of the cylinder when one of said 10 relatively movable parts is moved toward the other and having a small perforation therethrough coating with the liquid in said cylinder to limit the movement of separation of said parts.
- 15 6. A toy dump truck comprising a chassis, a body pivoted thereon to tilt, a body-tilting spring motor pivotally connected to said chassis and to said body, the spring of said motor being tensioned during the return 20 movement of said body to its normal position on the chassis, releasable means for retaining said body in said normal position, said motor comprising a fluid check for limiting the speed of movement of said body 25 toward the position of dumping.
7. A toy dump truck comprising a chassis, a body pivoted thereon to tip about a horizontal axis near the rear end thereof, a body-tilting spring motor of the compression type 30 pivotally connected to said chassis below the upper level thereof and also pivotally connected to said body, the point of connection between said motor and said body being between said horizontal axis and the point 35 of connection of said motor and chassis and

at a higher elevation than either said axis or said last named point of connection.

8. A toy truck comprising a chassis, a body pivoted thereon to tilt about a horizontal axis near the rear end thereof, a body-tilting motor interposed between the chassis and body, said motor including a cylinder pivotally connected at its front end to the chassis and inclined rearwardly and upwardly therefrom, a piston for said cylinder 40 pivotally connected to said body, a spring in said cylinder between the front end thereof and said piston to tilt said body and to be tensioned by the return movement thereof, said cylinder having therein liquid and the 45 parts being arranged to permit rapid movement of the piston in a direction such as to tension said spring but constraining the piston to a much slower movement in the direction such as to tilt said body. 50

9. A toy truck comprising a chassis, a body carried thereby and movably connected thereto, a spring motor mechanism carried by the chassis and operatively connected to said body to move the latter away from an 55 initial position, the parts being constructed and arranged to cause the spring of said motor mechanism to be tensioned during the return movement of the body, said motor mechanism including means for limiting the 60 speed of movement of the body away from said initial position.

In testimony whereof I affix my signature.

EDWARD L. WOOD.
